UNITED STATES PATENT OFFICE.

CARL EUGENE MELLIN, OF SCHENECTADY, NEW YORK.

FLUID-PRESSURE TURBINE.

Application filed June 6, 1919. Serial No. 302,175.

To all whom it may concern:

Be it known that I, CARL EUGENE MELLIN, of Schenectady, in the county of Schenectady and State of New York, have invented a certain new and useful Improvement in Fluid-Pressure Turbines, of which improvement the following is a specification.

My invention relates to turbines adaptable for operation by steam or other fluid pressure, and particularly to the type thereof in which blades or buckets are carried on a plurality of discs or plates secured on a rotatable shaft. The object of my invention is to provide a turbine of such type which shall be of simple, strong, and inexpensive construction, and low maintenance cost, and in the operation of which the energy of the actuating fluid shall be efficiently exerted with the lowest practicable resistance from friction and axial forces.

The improvement claimed is hereinafter fully set forth.

In the accompanying drawings: Figure 1 is a view, half in end elevation, and half in vertical transverse section, on the line *a a* of Fig. 2, of a fluid pressure turbine, illustrating an embodiment of my invention; Fig. 2, a vertical longitudinal section through the same, on the line *b b* of Fig. 1; Figs. 3 and 4, partial transverse sections, on an enlarged scale, illustrating, respectively, different forms of buckets; and, Figs. 5, 6, 7 and 8, partial longitudinal sections, illustrating variations of structural detail in the blades and carrying discs.

In the practice of my invention, referring descriptively to the specific embodiment thereof which is herein exemplified, a main or driving shaft, 1, is journaled in bearings, 2^a, fixed upon a frame, or bed plate, 2, which, in this instance, is shown as formed integral with the heads, 3^a, of the turbine casing, 3. The shaft, 1, passes through stuffing boxes, 3^b, in the heads of the casing, and has secured upon it, within the casing, a wheel or rotor, which is in the form of one or more plates or discs, 4, a plurality thereof being herein illustrated. Motive fluid is admitted to the casing, at its periphery, from a supply passage, 5, through nozzles, 6, inclined at an acute angle to the periphery of the casing, and controlled by valves, 7, in the ordinary manner. The motive fluid impinges at an acute angle on blades or buckets fixed on the plates, 4, thereby imparting rotary motion

to said plates and the driving shaft, 1, after which impingement it is discharged from the opposite side of the casing, through an exhaust passage, 8, to the atmosphere or to 60 a condenser.

A plurality of blades or buckets, 9, is rigidly secured to each of the plates or discs, 4, said blades being inwardly curved or inclined, at an acute angle, to tangents 65 of these circular plates, and forming the walls of passages through which the motive fluid which is supplied to the casing, from the nozzles, 6, at a more or less acute angle to the periphery of the casing, passes to the 70 interior of the casing, and thence to the exhaust passage, 8. The blades, 9, may be either curved, as shown, or straight, and are terminated, at their inner ends, by heads, 9^a, extending laterally from their 75 bodies, the faces of which heads are curved or inclined transversely to the middle lines of the plates, thereby causing the passages between them to be turned inwardly at their inner or discharge ends, by which an 80 approximate reversal of the currents of motive fluid is effected as it leaves them. The blades may be either toothed or notched on one or both sides, or have unbroken or plain surfaces. The toothed or notched 85 form of blades, which is illustrated in Figs. 1 and 3, is deemed preferable by me, for the reason that the teeth or notches cause the currents of motive fluid to expend their inertia more effectively, and in a shorter 90 distance, than if the walls of the passages were smooth or plain, as in the form shown in Fig. 4.

The velocity of the currents entering the passages between the blades is three to 95 four times as great as that of the peripheries of the plates, and the currents impinge against the teeth at oblique angles, and are deflected in and out, in a zig-zag course. The higher velocity of the current induces 100 a reduction of pressure on what may be termed the lee sides of the teeth, i. e., those opposite the driving sides on which the currents act, as the fluid expands radially from the middle lines of the currents, which 105 are carried forward, similarly to the gases leaving the muzzle of a gun, and the action of the currents against the lee sides of the teeth becomes considerably less than on the driving sides. In other words, a reduction 110 of pressure or partial vacuum is caused on the lee sides of the teeth, the difference of

pressure between which and the impact pressure on the driving sides constitutes the impelling force on each tooth. The center or core of the current does not follow the contour of the toothed or notched passage, but makes a partial deflection between the two sides, imparting speed to the sides of the current that are in contact with the walls of the passage.

10 The friction of the current of motive fluid on the sides of the passage is also a substantial impelling force, as the resultant from both sides falls the same as the teeth, close to a tangent of the plate with a proper curvature or inclination of the passage. While some heat is generated by the friction, this serves to delay condensation to the discharge portion of the passage and contributes in maintaining a higher velocity 15 of the current in the latter part of its path.

20 By reason of centrifugal force, water of condensation will not follow dry steam to its exhaust, but is separated therefrom in the passage between the blades and discharged 25 through passages, 9^b, to the periphery of the plate, after having given up all its inertia above that due to the velocity of the plate. The direction of this passage being opposite to the flow of the steam, the steam cannot 30 enter it.

35 The blades, 9, and consequently the passages between them, are preferably gradually widened, as shown, from the periphery of the plates on which they are carried, towards the shaft, to afford freedom for expansion of the motive fluid, and an increased area for the action of the decreasing velocity 40 of the currents, as they approach the inner ends of these paths. To effect this widening 45 of the blades, the portions of the plates, 4, to which the blades are attached, may be outwardly or laterally tapered or inclined, this inclination being formed on the inner sides only of the end plates, when a plurality of plates is applied, and on both sides 50 of the intermediate plates, which then become of V section adjacent to their peripheries, as clearly shown in Fig. 2. The V section plates are shown, on a larger scale, in Figs. 5 and 8.

55 The blades, 9, may be made integral with the plates or be welded thereto, or be separate pieces secured to the plates by bolts, 9^c, or rivets. The plates should be recessed by annular grooves, to form abutment shoulders for the blades, for the purpose of opposing the centrifugal force which tends to separate the blades from the plates when rotating at high speed. When the turbine 60 comprises a plurality of plates, as in the instance exemplified, the blades of adjacent plates may abut midway between the plates, as shown in Fig. 1, each of the plates, except the end ones, having blades on each side, as 65 shown on a larger scale in Fig. 5. Figs. 6,

7, and 8 illustrate the relation of the plate and blades, when only one plate is applied in the turbine, that of Fig. 6 having blades on one side only, and those of Figs. 7 and 8 having blades on both sides. In each of 70 these constructions, the sides of the passages between the plates which are further from the plates, are closed by rings, 9^a, of plate metal, between which and the plates, the blades are held rigidly by the bolts, 9^c. 75 When the blades are made separate from the plates, they may be formed by drop forging, without finishing on their toothed sides, except at their ends.

80 The plates, 4, should be made of the strongest material, in order to be as light as possible, and when spoked, the spokes should be shaped to act in the manner of fans, to facilitate the flow of the exhaust motive fluid from the inside of the casing to the atmosphere or the condenser, that is to say, their transverse sides should be inclined to lead in the direction of the rotation of the shaft, as indicated in Figs. 1, 3 and 4.

85 The casing, 3, of the turbine, is herein 90 shown as diametrically divided horizontally, but may be divided on an angle, in which case fluid supply nozzles may be disposed directly or diametrically opposite each other, and a greater number of nozzles can be conveniently applied around the casing, and by placing them as closely together as possible, the currents through the passages between the blades may be made practically continuous for two thirds or three quarters of the 100 periphery of the casing. Forward and reverse plates and blades may, if desired, be located in a single casing, suitable change valves being applied to turn the fluid pressure from the rotatory members of one direction to those of the other, or the forward and reverse members may be located in separate casings, as circumstances may render 105 more desirable.

110 It will be seen that the turbine above described is structurally simple, can be manufactured almost entirely by machine work, and is of ample strength, containing no members which are reasonably liable to breakage in service. Its cost of construction and 115 maintenance will be the least of any motor of the type of equal power, and the weight and space occupied should not exceed those of any other motor of equal power. Substantially all the energy of the motive fluid, 120 in leaving the supply nozzle or nozzles, is converted into power, less that that may be retained in exhaust steam after it has left the blades, as all friction exerted works practically tangentially to the rotating plate, and 125 the heat thereby generated serves to delay condensation. Thus there is little or no loss due to condensation of steam, no loss in axial forces, and no loss in friction of thrust bearings, none being required.

I claim as my invention and desire to secure by Letters Patent:

1. A fluid pressure turbine wheel having a plurality of blades with a plurality of notches on their working faces and each blade terminating in an enlarged head at its inner end, comprising forwardly and rearwardly extending curved portions.
2. A fluid pressure turbine wheel having a plurality of blades extending inwardly from the periphery of the wheel, and each blade terminating in an enlarged head at its inner end, comprising a forwardly and rearwardly extending curved portion.
3. A fluid pressure turbine wheel having a plurality of discs and a plurality of interposed blades, said blades provided with ridges and extending inwardly from the periphery of the wheel, each blade terminating in an enlarged head at its inner end, comprising a forwardly and rearwardly extending curved portion, a casing inclosing

said discs and blades, fluid supply nozzles opening into the casing in position to discharge into the space between the blades, 25 and an exhaust passage leading out of said casing.

4. In a fluid pressure turbine, the combination of a shaft; a plurality of spoked plates secured thereon, the sides of the spokes 30 of said plates being transversely inclined to facilitate the flow of motive fluid; a plurality of blades interposed between and fixed to said plates and extending inwardly from the periphery thereof, at acute angles to 35 radii; a casing enclosing said plates and blades; fluid supply nozzles opening into the casing, in position to discharge into the spaces between the blades; and an exhaust passage leading out of the casing.
